UNITED STATES PATENT OFFICE.

WILLIAM WARD DAVIDSON, OF EVANSTON, ILLINOIS, ASSIGNOR TO DAVIDSON MANUFACTURING COMPANY, OF MADISON, WISCONSIN, A CORPORATION OF WISCONSIN.

MACHINE FOR SEPARATING AND FEEDING BLANKS.

Application filed July 13, 1925. Serial No. 43,270.

This invention relates to machines for separating and feeding blanks and relates particularly to such machines of the general type which forms the subject-matter of an application for U. S. Letters Patent therefor, filed by me on November 21, 1922, and numbered serially 602,359.

Machines of the general type to which the invention of the present application relates, comprise a vertically movable blank supporting table, actuating means therefor, comprising a ratchet wheel and pawl, a vertically movable separator unit comprising a separator roll which, in operation, is adapted to rest upon the uppermost blank of a pack supported on said blank supporting table, pawl actuating means, and means to render the same inactive, controlled by upward movement of the separator unit, the relation being such that said pawl will "idle" when the separator roll is in the position, approximately, in which it will operate most effectively. In the operation of the machine, this position of the separator roll is defined by the height of the pack of blanks in the machine where said separator roll rests upon it, regardless of its height elsewhere.

In the machine of my said prior application Serial No. 602,359, operation of the actuating pawl is controlled by an oscillating member adapted to contact directly with the top of the pack of blanks on the blank supporting table, the relation being such that when the level of the top of the pack attains a predetermined height, said actuating pawl will be maintained inactive, but will become active when the top of the pack falls below said predetermined level. Specifically, said control member consists of an oscillating arm, mounted at the outer end of which is an anti-friction roller which is adapted to contact with the uppermost blank of the pack as it approaches the upper limit of its movement.

Use in actual practice has shown, that the feed control mechanism of my said prior application may be objectionable under certain conditions, as for example, when feeding blanks which are warped so that, at some points, the pack will be higher or lower than the portion thereof with which the anti-friction roller on the control arm contacts, which may result in forcing the separator

unit upwardly against the stop which defines its extreme raised position, thus "jamming" the machine and preventing its designed operation.

The control mechanism of my said prior application may also be objectionable when feeding some kinds of stock, due to contact of the roller forming part of the control mechanism with the blanks, as they are withdrawn, which may produce a resistance to the withdrawal of the blanks and thus impair the designed operation of the separator mechanism.

The object of the present invention is to overcome the foregoing objectionable features and, in accordance with my invention, I attain this end by providing actuating mechanism for the blank supporting carriage, including means for rendering said actuating means inoperative, which is controlled entirely by upward movement of the separator unit, the relation being such that the actuating means for the blank supporting carriage will be inactive when the separator unit attains a position in its vertical movement corresponding to a predetermined position of the separator roll, preferably that position in which it will operate most effectively.

My improved pack supporting carriage actuating and control mechanism also comprises the various other features, combinations of features and details of construction hereinafter described and claimed.

In the accompanying drawings, in which my invention is fully illustrated,

Figure 1 is a fragmentary, substantially central, sectional elevation of a machine embodying my invention and improvements, looking towards the right from a position at the right of and facing the figure.

Figure 2 is a fragmentary side elevation of the right side of the machine from a position at the left of and facing the figure.

Figure 3 is a fragmentary detailed view of the actuating and control mechanism for the pack supporting carriage from the right side of Figure 2.

Figures 4 and 5 are substantially similar sectional side views on the line 4-4 of Fig. 3, showing the control mechanism in different operative positions.

Figure 6 is a detached top plan view of

the oscillating arm by which movement is imparted to the actuating pawl arm and its movement controlled; and

Figure 7 is a detached top plan view of said actuating pawl, and the pawl arm therefor.

As previously stated, the invention and improvements, which form the subject matter of the present application, relates to machines for separating and feeding blanks of the general type fully shown and described in my said prior application Serial No. 602,359.

However, as the present invention relates only to the mechanism for actuating and controlling the movement of the pack carriage, parts and features of the machine not germane to the present invention have been, for the most part, entirely omitted or, if shown at all, are shown diagrammatically, thus avoiding confusion, avoiding unnecessary description, and rendering the description of the invention of the present application clearer and more definite.

Describing my invention with particular reference to the drawings, *a* designates one of the side frames of the machine.

The pack of blanks to be separated and fed, the top of which is indicated by the line *b*, Fig. 1, is supported upon a blank supporting carriage, designated as a whole *C*, comprising frame members one of which is shown at *c*, which are rigidly connected by transverse rods 1, 2 and 3, and brackets 4 supported on the rods 1 and 3 so as to be adjustable towards and from each other, and which are adapted to be secured in adjusted positions by set screws threaded through bosses on said brackets in line with the supporting rods 1.

The pack of blanks rests directly upon a board 5 supported on arms 6 forming parts of the brackets 4, the plane of the top side of said bracket arms and the board 5 being substantially horizontal, whereby the pack of blanks will be supported flatwise and in substantially horizontal position.

The pack carriage *C* is bodily movable vertically, being confined and guided in its vertical movement by engagement of rigid parts thereof with guide bearings on the side frame members *a*. In the preferable construction shown, vertical spaced roller studs 7 project from the outer sides of the blank carriage *C* and engage guide grooves 8 formed in the adjacent sides of the frame members *a*.

The pack carriage *C* is supported by means of chain belts 9 connected thereto and which pass over sprocket wheels 10 secured to a shaft 11 rotatably mounted in suitable bearings in the side frame members *a*. The ends of said chain belts opposite to the ends thereof are attached to the pack supporting carriage

C hang free and weights 12 are preferably suspended therefrom, adapted to prevent jumping of said chain belts, calculated to cause disengagement thereof from the teeth of the sprocket wheels 10.

The pack carriage *C* is adapted to be raised both manually and by power, but can be lowered manually only.

As shown, the means for raising said pack supporting carriage by power is as follows:

Rotatably mounted in bearings in the side frame members *a* is a shaft 13 to which oscillating movement is imparted in operation by a lever arm 14 secured to said shaft, said lever arm being connected by a rod 15 with a driven part of the machine in connection with which my improved separating and feeding machine is used. Also, to provide for throwing the separating and feeding machine out of operation without stopping the machine to which it is applied, said lever arm 15 preferably is mounted on the rod shaft 13 so as to turn thereon, and is adapted to be secured thereto and disconnected therefrom by means of a suitable clutch. However, said clutch forms no part of my present invention and will not, therefore, be either shown or described herein.

The power means for driving the shaft 11 also comprises a ratchet gear, designated as a whole *D* so constructed and arranged that oscillation of the shaft 13 will impart step by step rotation to the shaft 11 in a direction to raise the pack carriage *C*. As shown, said ratchet gear comprises a ratchet wheel 16 mounted to turn on the shaft 13, secured to rotate with which is a pinion 17 which meshes with a gear 18 secured to the shaft 11. Step by step rotation is adapted to be imparted to the ratchet wheel 16 by an actuating pawl 19 pivoted upon a frame or support 20.

As shown, see particularly Fig. 7, said pawl frame or support 20 consists of arms 20' and 20² rigidly connected at their outer ends by a stud 21 upon which the pawl 19 is pivoted.

Said pawl 19 is maintained yieldingly in engagement with the teeth of the ratchet wheel 16 by a spring 22 opposite ends of which are connected to pins 23 and 24, secured in said pawl and in the arm 20² of the pawl carrying frame, respectively.

As shown, the ratchet wheel 16 is prevented from turning backwards—which would lower the pack carriage *C*—by a retaining pawl 25 pivoted to a pin 26 secured in the frame member *a* on which said ratchet gear *D* is mounted. The retaining pawl 25 is maintained normally in engagement with the teeth of the ratchet wheel 16 by a spring 27, opposite ends of which are connected to pins 28 and 29 secured, respectively, in the

outer end of said retaining pawl and in the frame member *a* of the machine.

For reasons presently explained, the pins 23 and 28 secured in the actuating and retaining pawls 19 and 25, respectively, project at the outer sides of said pawls.

In the operation of the machine the actuating pawl 19 is adapted to be advanced to impart step by step rotation to the ratchet wheel 16 by means of a tappet 31 formed on and which projects laterally from an arm 32 secured to the shaft 13 so as to turn or oscillate therewith, said tappet 31 being adapted to engage surfaces 33 on the arms 15 20² and 20² of the frame or support 20 to which the actuating pawl is pivoted, as said arm 32 approaches the limit of its advancement towards said frame 20.

As shown, also, a cam 34 is secured to or 20 formed on a lateral extension 35 of the arm 32, said cam comprising a circular tread portion 36 which is concentric with the axis of the shaft 13, and a cut-away portion 37. The function of said cam will presently be 25 described.

In accordance with my invention, the means for retracting the actuating pawl 19 comprises a lever designated, as a whole *E*, which is pivoted to the frame member *a* at 38. The lever *E* is connected to the arm 20² of the frame 20 which carries the actuating pawl, by a rod 39, which has pivotal connection to both said lever and arm, the means for connecting said rod to the lever 35 *E* being preferably constructed and arranged for adjusting the operative length of said rod. As shown the rod 39 has a hook 40 on its lower end adapted to engage a hole in the member 20² of the frame 20 and the 40 means for connecting said rod to the pivoted lever *E* consists of a stud 41 comprising a head 42 formed in which is a hole to which the rod 39 is fitted so as to be freely movable endwise. The operative length of said rod 45 is adapted to be adjusted by means of a nut 43 threaded to the end of said rod which projects through the head 42 of said stud and which is adapted to be secured in different adjusted positions by means of a lock 50 nut 44 threaded to the upper end of the rod 39, a nut lock consisting of a star shaped washer 45 being preferably inserted between the nuts 43 and 44.

As shown, the pivot stud 41 comprises a 55 shank 46 which is fitted to a bushing 47 comprising a body portion 48, which has screw threaded engagement with a hole in the lever *E*, and a head 49, a shoulder which engages a rigid part of the lever *E*, a lock washer 50 being preferably inserted between the shoulder of the head 49 and the lever *E*.

As shown, the shank of the pivoted stud 41 is secured in engagement with the bore of the bushing 47 by means of a cotter pin. 60 Applied to the lever *E* is a spring 51

adapted to turn said lever pivotally to retract the pawl, when said lever is free to respond thereto, in a direction to retract the pawl 19, opposite ends of said spring being attached to said lever and to a pin 52 secured in the frame member *a*.

In the operation of the machine, blanks supported upon the pack carriage *C* are adapted to be withdrawn one at a time, by means of a separator unit designated as a whole *F*, which is supported so as to be bodily movable vertically, and which comprises a separator roll indicated at 53, Fig. 1, adapted to rest upon the uppermost blank of a pack of blanks supported on the pack carriage. Per se, said separator unit forms no part of my present invention and need not, therefore, be shown or described in detail. A desirable and preferable form of separator unit is that which forms part of the blank separating and feeding machine which is the subject matter of my said prior application Serial No. 602,359, to which reference is here made for a description thereof in detail, both as regards construction and 80 operation.

As herein shown, said separator unit *F* is supported by means of a rod 54 pivoted in the ends of arms 55 secured to a rock shaft 56 mounted to turn in bearings in the side 95 frame members *a*. Said separator unit is supported in upright position by roller studs 57 on the frame thereof, which engage guide grooves or channels 58 in the side frame members *a* of the machine, see particularly 100 Fig. 1.

The weight of the separator unit is supported in part by a counter weight 59, which is adjustable lengthwise on lever arm 60 secured to the rock shaft 56. Simple means 105 for securing said lever arm to the rock shaft consists of a head 61 pinned or otherwise rigidly secured to the end of said rock shaft which projects through its bearing in the frame member *a*, formed in which is a 110 groove 62 to which said lever arm is fitted, being secured in engagement therewith by screws or similar means.

During the actuation of the separator and feed rolls to withdraw blanks separately 115 from a pack on the pack carriage *C*, the actuating pawl 19 is adapted to be maintained inactive by means provided for the purpose. As shown, said means consist of a roller stud 63 mounted at the end of the 120 lever arm *E* at the opposite side of its pivot 38 from the point of attachment thereto of the spring 51 for turning said lever arm pivotally to retract the pawl 19. Said roller stud is adapted to run in contact with the 125 tread portion 36 of the cam 34 on the arm 32 during the operation of the separating and feeding rolls, the relation being such that engagement of said roller stud with said cam surface will prevent said lever arm from 130

being turned pivotally by the spring 51 to retract the actuating pawl 19; and the relation being such also that during intermittent initiation of the separator roll, the 5 roller stud 63 will be above the portion 37 of said cam tread, which is cut back a sufficient distance below the tread portion 36, to permit the lever arm E to turn pivotally—when free to do so—a distance corresponding to desired retraction of the actuating pawl 19, say five or six teeth as a maximum.

In the operation of the machine, the actuating pawl 19 is adapted to be maintained inactive at intervals by means in association with the separator unit F, the relation being such that when the blank separator unit attains an elevation corresponding to a predetermined position of the separator 20 roll 53, in which it will operate most effectively, said actuating pawl will "idle", that is, will execute an oscillating movement less than the pitch of the ratchet wheel 16, but will become operative as blanks are fed from 25 the top of the pack on the pack carriage C, so that the position of the separator roll will be below said predetermined position.

In the preferable construction shown, the means for thus controlling the operation of 30 said actuating pawl 19 consists of a lock bar 64 pivoted upon the pin 52, the lower end of which is adapted to engage a rigid surface on the pivoted lever E, said surface comprising a section 65 which is concentric 35 with the axis of the pin 52 and a section 66 which is eccentric to the axis of said pin, and which diverges from the surface 65 in the direction of the pivot 38 of the lever E. For reasons presently explained, the surface 40 66 is provided with serrations 67, the relation being such that corresponding surfaces of said serrations will be normal to radial lines intersecting the same and which pass through the axis of the pin 52. The function of said serrations will presently appear.

When there are no blanks on the pack carriage C or when the level of the top of the pack of blanks is below the separator 50 roll 53, said separator roll being at the lower limit of its movement, the lock bar 64 will hang free, substantially as shown in dotted lines in Fig. 5, with its lower end over the eccentric portion 66 of the stop surface on 55 the pivoted lever E, the relation being such that when said lock bar is in this position it will permit maximum retraction of the lever E by the spring 51, thus imparting designed maximum rotation to the shaft 11 60 which carries the sprocket wheels 10 and a maximum step by step elevation of the pack carriage C.

My improved control mechanism also comprises means, rendered operative by upward 65 movement of the separator unit F, whereby,

as the separator roll approaches its position of maximum efficiency in operation, the lock bar 64 will be turned pivotally towards its position shown in full lines in Figs. 4 and 5, the distance separating its lower end from 70 the opposed stop surface 66 becoming gradually less and less—correspondingly limiting retraction of the actuating pawl—until, when the said lock bar is in position to contact with the portion 65 of said stop surface, retraction of the actuating pawl will be less than the pitch of the teeth of the ratchet wheel 16, whereupon said actuating pawl will merely "idle", that is will execute a short backward and forward movement 80 which, however, will be insufficient to permit said pawl to engage a tooth other than that with which it is in engagement at any given time.

Stated differently, when, in the operation 85 of the machine, the lock bar 64 is in position to engage the stop surface 65 of the lever E, it will maintain said lever in pivotal position corresponding, substantially, to engagement of the roller stud 63 with the cam 90 surface 36. Preferably, however, said cam and roller stud are so proportioned that when in engagement, they will turn the lever E pivotally to provide slight clearance between the lower end of the lock bar 64 and the stop surface 65, thus permitting free pivotal movement of said lock bar. Obviously this would not be the case if the lower end of said lock bar were held in frictional engagement with the stop surface by the 100 tension of the spring 51, as would be the case without said cam and roller stud, or equivalent means.

In operation, engagement of the roller stud 63 with the cam 36 will turn the lever 105 E pivotally to extend the spring 51 and restore its tension, the connection between the link 39 and stud 41 being constructed and arranged to permit pivotal movement of the said lever E in a direction corresponding 110 to advancement of the actuating pawl 19, independently of the rod 39.

The relation is such, however, that when the lock bar 64 is in a position above the stop surface 66 on the lever E and the roller stud 63 is over the cut-away section 37 of the cam 34, said lever will have capacity for pivotal movement to permit retraction of the actuating pawl a distance greater than the pitch of the teeth of the ratchet wheel 16, such retraction increasing as the lock bar 64 approaches the position shown in dotted lines in Fig. 5, in which position the capacity for pivotal movement of said lever E will correspond to designed maximum retraction 120 of the actuating pawl.

The function of the serrations 67 is to provide a number of short steps on said stop surface 66 at different distances from the axis of the pivot pin 52, which the end of 130

the lock bar 64 will engage at right angles, thus eliminating all components of force which might tend to turn said lock bar pivotally towards its dotted position, Fig. 5, if said stop surface were continuous and permit full retraction of the actuating pawl.

In the preferable construction shown, the means for imparting pivotal movement to the lock bar 64 as the separator unit F is raised, to bring said lock bar in the position shown in full lines in Figs. 4 and 5, consists of a pin 68 secured in an extension 69 of the counter-weighted lever 60, rearwardly from the rock shaft 56, which as the lever 60 turns pivotally, corresponding to raising movement of the separator unit, will engage a cam surface 70 formed on a head 71 on the pivoted end of the lock bar 64, the relation being such that, as the separator unit is raised into position corresponding to most efficient operation of the separator roll 53, said lock bar 64 will gradually be turned pivotally into the position shown in full lines in Figs. 4 and 5 of the drawings. In this position of the lock bar, the actuating pawl 19 will be inactive and will become and remain inactive until a sufficient number of blanks have been fed from the pack supported on the pack carriage C to permit the separator unit—and thus the separator roll 53—to lower a sufficient distance to permit the lock bar 64 to turn pivotally out of engagement with the stop surface 65 and to bring it over a serration 67 of the stop surface 66, which corresponds to retraction of the actuating pawl a distance equal to the pitch of the teeth of the ratchet wheel 16.

As shown, the pivotal position of the lock bar 64 corresponding to inaction of the actuating pawl 19 is defined by engagement of the pin 68 with a shoulder 72 at the upper end of the cam surface 70, said shoulder being preferably rounded to fit the pin 68. Obviously, the rounded shoulder 72 will form an abrupt divergent extension of the cam surface 70 in a direction to throw the lock bar 64 abruptly into position to engage the stop surface 65, as the separator unit approaches an elevation corresponding to inaction of the actuating pawl. This expedient obviates any necessity for nice adjustment of parts, which might otherwise be necessary.

To prevent disengagement of the lower end of the lock bar 64 from the stop surface 65 of the lever E and of the pin 68 from the head 71 on said lock bar, as should the separator unit be raised rapidly to the upper limit of its movement, causing the pin 68 to strike the shoulder 72 with a sharp impact which might throw its lower end beyond its contemplated extreme position, the stop surface 65 is extended a sufficient distance to insure that said lock bar will not pass out of engagement with said stop surface. Also,

the head 71 on said lock bar is extended upward beyond the shoulder 72 so that, even should the separator unit F be raised to the extreme limit of its elevation, it would be impossible for said pin to pass out of engagement with said head 71.

The contour of the extension of the head 71 of the lock bar 64 above the shoulder 72 is the arc of a circle—said arc being designated 73—which is concentric with the axis 75 of the rock shaft 56, when the pin 68 is in engagement with the shoulder 72.

To avoid fine fitting and to provide for making adjustments to compensate for wear of the parts, particularly in the pivot stud 63, the lever E preferably consists of separate parts 74 and 75, which are pivoted to each other at 76. The pivot bearing 38 for said lever is formed in and the roller stud 63 is mounted upon the part 76 of said lever, while the stop surfaces 65 and 66 are formed directly upon the part 75 thereof.

The parts 74 and 75 of said lever are adapted to be adjusted relative to each other into positions corresponding to desired operative relations of the roller stud 63 and the stop surfaces 65 and 66 by a thrust screw 77, which has screw threaded engagement with a boss on the part 74 of said lever, in line with the portion of the part 75 of said lever on which the stop surface 65 is formed, said thrust screw being adapted to be secured in adjusted positions by a lock nut.

When the parts 74 and 75 of said lever E have been adjusted into proper operative positions, they are adapted to be clamped rigidly together by the bushing 47 which has screw threaded engagement with a hole in the part 74 of said lever and which is positioned in a slot 78 formed in the part 75 of said lever, shown best in Fig. 6. Thus, when said bushing is screwed up, it will clamp the parts 74 and 75 of said lever together, unscrewing of said bushing being prevented by means of the lock washer applied thereto, as previously explained.

The pack carriage C is adapted to be raised manually by means of a crank 79 rigidly secured to the ratchet wheel 16 and the pinion 17, said crank, ratchet wheel and pinion being mounted on the shaft 13 so as to turn thereon. Said crank, ratchet wheel and pinion may thus be secured together and mounted by means of a bushing 80 to which they are keyed or otherwise secured, said bushing being provided with a bore fitted to the shaft 13 and said bushing is secured in engagement with the shaft 13 by means of a washer 81 secured to the outer end of said shaft 13 by a screw 82, the shank of which extends thru a hole in the said washer and has screw threaded engagement with a hole in the end of said shaft.

As shown the outer arm 20' of the pawl-carrying frame 20 is fitted to turn on the

bushing 80, while the inner arm 20² thereof is fitted to turn on the shaft 13.

With the described construction, it is obvious that rotation of the crank 79 in a direction to cause the teeth of the ratchet wheel 16 to overrun the pawls 19 and 25 will turn the gear 18 and the sprocket wheel shaft 11 in a direction to raise the pack carriage.

10 To lower the pack carriage it is first necessary to disengage both the actuating pawl 19 and the retaining pawl 25 from the teeth of the ratchet wheel 16, to permit the sprocket wheel shaft 11 to be turned backwards and, 15 to prevent the pack carriage from falling from its own weight or under the added weight of a pack of blanks carried thereby, the means for disengaging said pawls is preferably constructed and arranged so that 20 it may be operated with one hand only, leaving the other hand free to lower said pack carriage gradually by gripping the handle of the crank 79.

As shown, the means for disengaging said 25 pawls from the ratchet wheel consists of a lever 83 pivoted at one end to the side frame member *a* on which the ratchet gear D is mounted, and which is maintained normally in raised position by a spring 84 opposite 30 ends of which are secured to pins 85 and 86 secured, respectively, in said lever and in the frame member *a*.

Said lever 83 is adapted to be turned 35 pivotally against the force of the spring 84 by means of a pin 87 secured in the outer end therefrom and which projects inwardly towards the frame member *a*.

Pivots connected to said lever 83 is a 40 pawl retraction link 88 formed on which are projections 89 and 90 which extend over the pins 23 and 28 secured in the actuating pawls 19 and 25, respectively, and which, as previously explained, project at the outer sides of said pawls.

45 The pawl retraction link is confined in operative position relatively to the pins 23 and 28 by means of a stud 91 secured in the frame member *a*, the outer end of which is reduced and extends through a slot 92 formed in said pawl retraction link and is secured in engagement with said slot by means of a screw 93, which has screw threaded engagement with a hole in the end of the stud 91 and the head of which extends 55 outwardly so as to embrace the sides of said slot 92.

The lever 83 is maintained normally at the upper limit of its movement—defined by contact of the lower end of the slot 92 60 with the stud 91—by the spring 84, said slot being made sufficiently long to provide for pivotal movement of the lever 83 to depress the projections 89 and 90 on the pawl retraction link into engagement with the pins 23 and 28 secured in the pawls 19

and 25, and to turn said pawls pivotally to retract them out of engagement with the teeth of the ratchet wheel 16.

With the described construction, it is obvious that the pawls 19 and 25 may be retracted by depressing the lever 83 with one hand, leaving the other hand free to turn the crank 79 to lower the pack carriage C.

The pin 23 secured in the actuating pawl 19 will oscillate with the frame 20 on which 75 said pawl is mounted and to insure disengagement of said actuating pawl by the retraction link 88, under all operating conditions, the projection 89 on said link extends beyond the pin 23—when the actuating 80 pawl is in its position of extreme advancement—a distance slightly greater than the traverse of said pawl.

In accordance with my invention, also, I preferably provide safety means to prevent falling of the pack carriage C when the lever 83 is turned to disengage the pawls 19 and 25 from the teeth of the ratchet wheel 16, should the handle of the crank 79 slip out of the operator's hand in lowering 90 the pack carriage.

What I now consider preferable means for this purpose, consists of a projection 94 on the lever 83 which, when said lever is in its position of extreme depression, will 95 project into the path of movement of a rigid part of the crank 79, but will be out of the path of movement thereof when said lever is at the upper limit of the movement, thus permitting said crank to be turned freely 100 by hand to raise the pack carriage.

As shown, the projection on the crank 79 consists of a pin 95 mounted so as to be movable endwise in bearings in the crank handle 96, said rod being maintained yieldably extended so as to engage the safety projection 94 on the lever 83, when said lever is depressed, and being adapted to be retracted manually to permit it to pass said safety projection, when it is desired to lower 110 the pack carriage.

As shown, the means for mounting said pin 95 are as follows:—Formed on the crank 79 is a handle support 97 formed lengthwise in which is a hole comprising an outer 115 relatively large portion 98 and an inner relatively small portion 99. The pin 95 is fitted to the relatively large portion 98 of the handle portion of the crank and formed thereon is a shank 100 which extends through a hole formed in the end of said handle support 97 remote from the crank arm 79. The pin 95 is maintained yieldingly extended by a spring 101 which reacts between a shoulder 102 at the inner end of the pin 95 and the inner end of the relatively small hole 99 in said handle support 97, and which surrounds the shank 100 of said pin, as a guide. The pin 95 is maintained in engagement with the hole 98 in the crank by a head 103 se- 120

cured to the outer end of the shank 100 of said pin and to provide a smooth hand grip, the parts of the portion of the crank herefore described are enclosed by a sleeve 104 fitted to bearings formed on the handle support 97 adjacent to the crank arm 79 and on the head 103. As shown, the head 103 is secured to the shank 100 by a screw 105, comprising a shank which extends thru a hole formed in the end of the shank 100 of the pin 95 and has screw threaded engagement with a hole formed in said head 103. As shown, the head of said screw is relatively long, its outer end being preferably substantially flush with the surface of the sleeve 104.

Retraction of the pin 95 to permit it to pass the safety projection 94 on the lever 83 when the lever 83 is depressed, may obviously be effected by drawing the sleeve 104 outwardly into the position shown in dotted lines, Fig. 4, which conveniently can be done by the hand of the operator used for turning said crank.

Retraction of the pin 95 is limited by contact of the shoulder at its inner end with the shoulder formed between the large and small portions 98 and 99 of the hole in the handle supporting portion 97 of the crank.

I claim:

1. In a blank separating machine of the type specified, the combination of a vertically movable pack carriage, means for raising and lowering said pack carriage comprising power actuated means for raising the same, a vertically movable blank separator unit comprising a rotatable separator roll adapted to rest upon the uppermost blank of a pack of blanks on the pack carriage, the relation being such that, in operation, the separator roll will at all times rest upon the pack, means for rotating said separator roll in a direction to advance the blanks, and means actuated and controlled solely by upward movement of said separator unit for rendering the power actuated means for raising said pack carriage inactive when said separator unit attains a predetermined position.

2. In a blank separating machine of the type specified, the combination of a vertically movable pack carriage, means for raising and lowering said pack carriage comprising power actuated means for raising the same, a vertically movable blank separator unit comprising a rotatable separator roll adapted to rest upon the uppermost blank of a pack of blanks on the pack carriage, the relation being such that in operation the separator roll will at all times rest upon said pack, means for rotating said separator roll upon a substantially stationary axis, and means actuated and controlled solely by upward movement of said separator

unit for rendering the power actuated means for raising said pack carriage inactive when said separator unit attains a position corresponding to that of most effective operation of the separator roll.

3. In a blank separating machine of the type specified, the combination of a vertically movable pack carriage, means for raising and lowering said pack carriage comprising power actuated means for raising the same, a vertically movable blank separator unit comprising a rotatable separator roll adapted to rest upon the uppermost blank of a pack of blanks on said pack carriage, the relation being such that, in operation, the separator roll will at all times rest upon said pack, the power actuated means for raising said pack carriage comprising ratchet gearing, and means actuated and controlled solely by upward movement on the separator unit for limiting retraction of the actuating pawl of the ratchet gearing.

4. A blank separating machine as specified in claim 1, which also comprises manually operated means for disconnecting said pack carriage actuating means and manually operated means for controlling the lowering thereof.

5. A blank separating machine as specified in claim 1, which also comprises means for disconnecting said pack carriage actuating means, means for controlling the lowering of said pack carriage, and means to prevent falling of the pack carriage when said actuating means is disconnected.

6. A blank separating machine as specified in claim 1, which also comprises means for disconnecting said pack carriage actuating means, means for controlling the lowering of said pack carriage, and manually operated means to prevent falling of the pack carriage when said actuating means is disconnected.

7. A blank separating machine as specified in claim 1, which also comprises means for disconnecting said pack carriage actuating means, means for controlling the lowering of said pack carriage, and manually operated means to prevent falling of the pack carriage when said actuating means is disconnected rendered operative by disconnecting the pack carriage actuating means.

8. A blank separating machine as specified in claim 3, in which the ratchet gearing comprises a ratchet wheel, actuating and retaining pawls and manually operated means for disengaging said pawls from said ratchet wheel to permit lowering of the pack carriage.

9. A blank separating machine as specified in claim 3, in which the ratchet gearing comprises a ratchet wheel, actuating and retaining pawls, means for disengaging said pawls from said ratchet wheel to permit

lowering of the pack carriage, and a crank applied to the driven shaft for turning the same by hand.

10. A blank separating machine as specified in claim 3, in which the ratchet gearing comprises a ratchet wheel, actuating and retaining pawls, means for disengaging said pawls from said ratchet wheel and means to prevent the pack carriage from falling when said pawls are disengaged.

11. A blank separating machine as specified in claim 3, in which the ratchet gearing comprises a ratchet wheel, actuating and retaining pawls, means for disengaging said pawls from said ratchet wheel to permit lowering of the pack carriage comprising a manually operable lever, projections on said pawls, a link connected to said lever, projections thereon adapted to engage the projections on said pawls, and a spring applied to said lever adapted to turn it to retract the projections on said link from engagement with the projections on said pawls.

12. A blank separating machine as specified in claim 3, in which the ratchet gearing comprises a ratchet wheel, actuating and retaining pawls, a crank applied to the driven shaft for turning the same by hand, means for disengaging said pawls from said ratchet wheel, and means to prevent the pack carriage from falling when said pawls are disengaged, the means for disengaging the pawls from the teeth of the ratchet wheel consisting of a manually operable pivoted lever, projections on said pawls, a link connected to said lever, projections thereon adapted to engage the projections on said pawls, and a spring applied to said lever adapted to turn it to retract the projections on said link from engagement with the projections on said pawls.

13. A blank separating machine as specified in claim 3, in which the ratchet gearing comprises a ratchet wheel, actuating and retaining pawls, a crank applied to the driven shaft, means for disengaging said pawls from said ratchet wheel, and means to prevent the pack carriage from falling when said pawls are disengaged, the means for disengaging the pawls from the teeth of the ratchet wheel consisting of a manually operable lever, projections on said pawls, a link connected to said lever, projections thereon adapted to engage the projections on said pawls, and a spring applied to said lever adapted to turn it to retract the projections on said link from engagement with the projections on said pawls, and the means for preventing the pack carriage from falling consisting of a projection on said pawl retracting lever, and a pin on the crank applied to the driven shaft.

driven shaft, the relation being such that the projection on said pawl retracting lever will be out of the path of movement of the pin on said crank when said lever is in position corresponding to engagement of the pawls with the teeth of the ratchet wheel and will project into the path of movement of said pin when said lever is in position to disengage said pawls, the pin on the crank being movable, a spring applied thereto adapted to maintain it normally extended, and manually operable means for retracting said pin.

14. A blank separating machine as specified in claim 3, in which the ratchet gearing comprises a ratchet wheel, actuating and retaining pawls, a crank applied to the driven shaft, means for disengaging said pawls from said ratchet wheel, and means to prevent the pack carriage from falling when said pawls are disengaged, the means for disengaging the pawls from the teeth of the ratchet wheel consisting of a manually operable lever, projections on said pawls, a link connected to said lever, projections thereon adapted to engage the projections on said pawls, and a spring applied to said lever adapted to turn it to retract the projections on said link from engagement with the projections on said pawls, and the means for preventing the pack carriage from falling consisting of a projection on said pawl retracting lever, and a pin on the crank applied to the driven shaft, the relation being such that the projection on said pawl retracting lever will be out of the path of movement of the pin on said crank when said lever is in position corresponding to engagement of the pawls, and will project into the path of movement of said pin when said lever is in position corresponding to disengagement of said pawls, the pin on the crank being movable endwise, and a spring applied thereto adapted to maintain it normally extended, the handle of said crank comprising a grip portion which is movable endwise, and connection between said grip portion and pin providing means for retracting said pin.

15. In a blank separating machine of the type specified, the combination of a vertically movable pack carriage, means for raising and lowering said pack carriage comprising power actuated means for raising the same, a vertically movable blank separator unit, comprising a frame and a separator roll rotatably mounted therein adapted to rest upon the uppermost blank of a pack of blanks on said pack carriage, the power actuated means for raising said pack carriage comprising driving and driven shafts, means adapted for imparting oscillating movement to said driving shaft in

operation, ratchet gearing connecting said driving and driven shafts, and connection between the driven shaft and the pack carriage, means for limiting retraction of the actuating pawl to a desired maximum when the separator unit is at the lower limit of its movement, and means controlled by raising movement of the separator unit for reducing retraction of the actuating pawl to a distance less than the pitch of the teeth of the ratchet wheel when said separator unit attains a predetermined position.

16. In a blank separating machine of the type specified, the combination of a vertically movable pack carriage, means for raising and lowering said pack carriage comprising power actuated means for raising the same, a vertically movable blank separator unit, comprising a frame and a separator roll rotatably mounted therein adapted to rest upon the uppermost blank of a pack of blanks on said pack carriage, the power actuated means for raising said pack carriage comprising driving and driven shafts, means adapted for imparting oscillating movement to said driving shaft in operation, ratchet gearing connecting said driving and driven shafts, and connection between the driven shaft and the pack carriage, means for limiting retraction of the actuating pawl to a desired maximum when the separator unit is at the lower limit of its movement, and means controlled by raising movement of the separator unit for gradually reducing retraction of the actuating pawl to a distance less than the pitch of the teeth of the ratchet wheel when said separator unit attains a predetermined position.

17. A blank separating machine as specified in claim 15, in which the means for retracting the actuating pawl of the ratchet gearing and for controlling retraction of said pawl, comprises a pivoted lever, a link which connects said lever with the support for said pawl, a spring applied to said lever adapted for turning the same to retract said pawl, means in association with said lever and controlled by raising movement of the separator unit for reducing the pivotal movement of said lever to an arc corresponding to retraction of the actuating pawl a distance less than the pitch of the teeth of the ratchet wheel when the separator unit attains a predetermined position.

18. A blank separating machine as specified in claim 15, in which the means for retracting the actuating pawl of the ratchet gearing and for controlling retraction of said pawl, comprises a pivoted lever, a link which connects said lever with the support for said pawl, a spring applied to said lever adapted for turning the same to retract said pawl, means in association with said lever and controlled by raising movement of the separator

unit for reducing the pivotal movement of said lever to an arc corresponding to retraction of the actuating pawl a distance less than the pitch of the teeth of the ratchet wheel when the separator unit attains a predetermined position, the connection of said link to one of the parts connected thereby being constructed and arranged to permit movement of said pivoted lever in a direction corresponding to advancement of said actuating pawl independently of the support for said actuating pawl.

19. A blank separating machine as specified in claim 15, in which the means for retracting the actuating pawl of the ratchet gearing and for controlling retraction of said pawl, comprises a pivoted lever, a link which connects said lever with the supporting member for said actuating pawl, a spring applied to said lever adapted for turning the same to retract said pawl, a pivoted lock bar, and a stop surface formed on said pivoted lever adapted to be brought into contact with the end of said lock bar by pivotal movement of said lever, said stop surface comprising sections which are relatively proximate to and remote from the pivot of said lock bar, and means controlled by raising movement of the separator unit for turning said lock bar pivotally.

20. A blank separating machine as specified in claim 15, in which the means for retracting the actuating pawl of the ratchet gearing and for controlling retraction of said pawl, comprises a pivoted lever, a link which connects said lever with the supporting member for said actuating pawl, a spring applied to said lever adapted to turn it to retract said pawl, a pivoted lock bar, and a stop surface formed on said lever adapted to be brought into contact with the end of said lock bar by pivotal movement of said lever, said stop surface comprising sections which are relatively proximate to and remote from the pivot of said lock bar, the proximate section being concentric with the pivot of said lock bar, and means controlled by raising movement of the separator unit for turning said lock bar pivotally.

21. A blank separating machine as specified in claim 15, in which the means for retracting the actuating pawl of the ratchet gearing and for controlling retraction of said pawl, comprises a pivoted lever, a link which connects said lever with the supporting member for said actuating pawl, a spring applied to said lever adapted to turn it to retract said pawl, a pivoted lock bar and a stop surface formed on said lever which is adapted to be brought into contact with the end of said lock bar by pivotal movement of said lever, said stop surface comprising sections which are relatively proximate to and remote from the pivot of said lock bar, the

proximate section being concentric with the pivot of said lock bar, and the remote section being eccentric relative to the pivot of said lock bar, and means controlled by raising movement of said separator unit to turn the lock bar pivotally.

22. A blank separating machine as specified in claim 15, in which the means for retracting the actuating pawl of the ratchet 10 gearing and for controlling retraction of said pawl, comprises a pivoted lever, a link which connects said lever with the supporting member for said actuating pawl, a spring applied to said lever adapted to turn it to retract said pawl, a pivoted lock bar and a stop surface formed on said lever adapted to be brought into contact with the end of said lock bar by pivotal movement of said lever comprising sections which are relatively 15 proximate to and remote from the pivot of said lock bar, means controlled by raising movement of the separator unit to turn said lock bar pivotally, and means to turn said lever pivotally to retract the stop surface on said pivoted lever from contact with the end of said lock bar between actuations of said lever to retract the actuating pawl.

23. A blank separating machine as specified in claim 15, in which the means for retracting the actuating pawl of the ratchet 30 gearing and for controlling retraction of said pawl, comprises a pivoted lever, a link which connects said lever with the supporting member for said actuating pawl, a spring applied to said lever adapted to turn it to retract said pawl, a pivoted lock bar and a stop surface formed on said lever adapted to be brought into contact with the end of said lock bar by pivotal movement of 35 said lever comprising sections which are relatively proximate to and remote from the pivot of said lock bar, means controlled by raising movement of the separator unit to turn said lock bar pivotally, and means to turn said lever pivotally to retract the stop surface on said pivoted lever from contact with the end of said lock bar between actuations of said lever to retract the actuating pawl consisting of 40 a cam secured to the driving shaft and a stud on said lever adapted to engage said cam.

24. A blank separating machine as specified in claim 15, in which the means for 55 retracting the actuating pawl of the ratchet gearing and for controlling retraction of said pawl, comprises a pivoted lever, a link which connects said lever with the supporting member for said actuating pawl, a spring applied to said lever adapted to turn it to retract said pawl, a pivoted lock bar and a stop surface formed on 60 said lever adapted to be brought into contact with the end of said stop bar by pivotal movement of said lever, and means

controlled by raising movement of the separator unit to turn said lock bar pivotally comprising a head formed on said lock bar, a cam surface thereon and a pin secured in a part which moves with said separator unit 70 adapted to engage the cam surface on the head of said lock bar.

25. A blank separating machine as specified in claim 15, in which the means for retracting the actuating pawl of the ratchet 75 gearing and for controlling retraction of said pawl, comprises a pivoted lever, a link which connects said lever with the supporting member for said actuating pawl, a spring applied to said lever adapted to turn 80 it to retract said pawl, a pivoted lock bar and a stop surface formed on said pivoted lever adapted to be brought into contact with the end of said lock bar by pivotal movement of said lever, and means controlled by raising movement of the separator unit for turning said lock bar pivotally, comprising a head formed on said lock bar, a cam surface thereon and a pin secured in a part which moves with said separator 85 unit adapted to engage the cam surface on the head on said lock bar, the head on said lock bar extending above the control pin to prevent disengagement of said pin and lock bar from each other.

26. A blank separating machine as specified in claim 15, in which the means for retracting the actuating pawl of the ratchet gearing and for controlling retraction of said pawl, comprises a pivoted lever, a link which connects said lever with the supporting member for said actuating pawl, a spring applied to said lever adapted to turn it to retract said pawl, a pivoted lock bar, and a stop surface formed on said lever adapted to be brought into contact with the end of said lock bar by pivotal movement of said lever, said stop surface comprising sections which are relatively proximate to and remote from the pivot of said lock 100 bar, the proximate section being concentric with the pivot of said lock bar, and means controlled by raising movement of the separator unit for turning said lock bar pivotally, the stop surface on said pivoted lever being sufficiently long to prevent disengagement of the lock bar therefrom.

27. A blank separating machine as specified in claim 15, in which the means for retracting the actuating pawl of the ratchet 105 gearing and for controlling retraction of said pawl, comprises a pivoted lever, a link which connects said lever with the supporting member for said actuating pawl, a spring applied to said lever adapted to turn it to retract said pawl, a pivoted lock bar and a stop surface formed on said lever which is adapted to be brought into contact with the end of said lock bar by pivotal movement of said lever, said 110

stop surface comprising sections which are relatively proximate to and remote from the pivot of said lock bar, the proximate section being concentric with the pivot of said lock bar, and the remote section being eccentric relative to the pivot of said lock bar, and means controlled by raising movement of said separator unit to turn the lock bar pivotally, the eccentric section of the stop surface on the said pivoted lever being serrated.

28. A blank separating machine as specified in claim 15, in which the means for retracting the actuating pawl of the ratchet gearing and for controlling retraction of said pawl, comprises a pivoted lever, a link which connects said lever with the supporting member for said actuating pawl, a spring applied to said lever adapted to turn it to retract said pawl, a pivoted lock bar, and a stop surface formed on said pivoted lever adapted to be brought into contact with the end of said lock bar by pivotal movement of said lever, said stop surface being adjustable and comprising sections which are relatively proximate to and remote from the pivot of said lock bar, and means controlled by upward movement of the separator unit for turning said lock bar pivotally.

29. A blank separating machine as specified in claim 15, in which the means for retracting the actuating pawl of the ratchet gearing and for controlling retraction of said pawl, comprises a pivoted lever, a link which connects said lever with the supporting member for said actuating pawl, a spring applied to said lever adapted for turning the same to retract said pawl, a pivoted lock bar, and a stop surface formed on said pivoted lever adapted to be brought into contact with the end of said lock bar by pivotal movement of said lever, said lever comprising separate adjustably connected parts, one thereof being pivoted to a fixed support, and the other bearing the stop surface, and means for securing the parts of said lever together in fixed relation.

30. A blank separating machine as specified in claim 15, in which the means for retracting the actuating pawl of the ratchet gearing and for controlling retraction of said pawl, comprises a pivoted lever, a link which connects said lever with the supporting member for said actuating pawl, a spring applied to said lever adapted for turning the same to retract said pawl, a pivoted lock bar, and a stop surface formed on said pivoted lever adapted to be brought into contact with the end of said lock bar by pivotal movement of said lever, said lever comprising separate adjustably connected parts, one thereof being pivoted to a fixed support, and the other bearing the stop sur-

face, means for effecting adjustment of the 65 part of said lever which bears the stop surface relative to the other part of the lever and means for securing said parts together in fixed relation.

31. A blank separating machine as specified in claim 15, in which the means for retracting the actuating pawl of the ratchet gearing and for controlling retraction of said pawl, comprises a pivoted lever, a link which connects said lever with the supporting member for said actuating pawl, a spring applied to said lever adapted for turning the same to retract said pawl, a pivoted lock bar, and a stop surface formed on said pivoted lever adapted to be brought 70 75 into contact with the end of said lock bar by pivotal movement of said lever, said lever comprising separate pivotally connected parts, one of which is pivoted to a fixed support, and the other of which bears the 80 85 stop surface, and means for securing said parts together in fixed relation.

32. A blank separating machine as specified in claim 15, in which the means for retracting the actuating pawl of the ratchet 90 gearing and for controlling retraction of said pawl, comprises a pivoted lever, a link which connects said lever with the supporting member for said actuating pawl, a spring applied to said lever adapted to 95 turn it to retract said pawl, a pivoted lock bar and a stop surface formed on said lever adapted to be brought into contact with the end of said lock bar by pivotal movement of said lever, comprising sections 100 which are relatively proximate to and remote from the pivot of said lock bar, means controlled by raising movement of the separator unit to turn said lock bar pivotally, and means to turn said lever pivotally to 105 retract the stop surface on said pivoted lever from contact with the end of said lock bar between actuations of said lever to retract the actuating pawl, said pivoted lever comprising separate adjustably connected parts, 110 one thereof being pivoted to a fixed support, and the other bearing the stop surface, and means for securing the parts of said lever together in fixed relation.

33. A blank separating machine as specified in claim 15, in which the means for retracting the actuating pawl of the ratchet gearing and for controlling retraction of said pawl, comprises a pivoted lever, a link which connects said lever with the supporting member for said actuating pawl, a spring applied to said lever adapted to turn it to retract said pawl, a pivoted lock bar and a stop surface formed on said lever adapted to be brought into contact with the 115 120 125 end of said lock bar by pivotal movement of said lever, comprising sections which are relatively proximate to and remote from the

pivot of said lock bar, means controlled by raising movement of the separator unit to turn said lock bar pivotally, and means to turn said lever pivotally to retract the stop 5. surface on said pivoted lever from contact with the end of said lock bar between actuators of said lever to retract the actuator-

ing pawl, consisting of a cam secured to the driving shaft and a stud on said lever adapted to engage said cam. 10

In witness that I claim the foregoing as my invention, I affix my signature this 24th day of June, 1925.

WILLIAM WARD DAVIDSON.
